METHOD OF MAKING TAPERED GROUND JOINTS

Walter O. Lueritzing, Vineland, N. J., assignor to
 Lurex Manufacturing Company, Vineland,
 N. J., a corporation of New Jersey

Application February 28, 1948, Serial No. 12,073

11 Claims. (Cl. 49—82)

1

This invention relates to the manufacture of glassware for chemical and like use and is concerned more particularly with a novel method of forming on a glass article a circumferential enlargement of tapering diameter which is receivable in a tapered socket to make a sealed joint of the plug and socket type. The method of the invention may be utilized in making articles of various kinds and may be employed to especial advantage in the manufacture of thermometers for use in chemical apparatus. The application of the new method in connection with the production of thermometers will, accordingly, be illustrated and described in detail for purposes of explanation, although it will be apparent that the utility of the method is not restricted to that specific use.

It is now common practice to construct thermometers, which are to be mounted in an opening in the wall of a vessel forming part of chemical apparatus, with a circumferential enlargement of plug form and having a ground outer surface of tapering diameter. The vessel is then made with a socket having a ground surface of corresponding taper and, when the thermometer is seated in the socket, the ground surfaces make a tightly sealed joint. Heretofore, the enlargement on the thermometer has been made by heating the thermometer stem between its ends with a flame and then slowly and carefully forcing the ends of the stem toward one another to force the softened glass outwardly to increase the outer diameter of the stem. The operation is carried on along the stem, until an enlargement of suitable diameter and length has been made, and it must be performed with great skill and attention, in order to avoid closure or distortion of the small passage through the stem. Because of the delicacy and skill required in the operation and the time consumed, the production of such thermometers is not only expensive but also most trying to the glass workers.

The present invention is directed to the provision of a method for making an enlargement on a glass article, such as a thermometer, which is relatively easy to perform, can be carried out rapidly, and is not likely to cause injury to the article, even though performed with only a moderate degree of skill. In the practice of the new method, a length of glass tubing is telescoped over the article and then secured thereto at the place, where the enlargement is desired, so that it forms an integral part of the article. The attaching of the tube to the article is effected by operations requiring a minimum distortion of the

2

article and, after the tube is in place, its outer surface can be finished by the usual operations.

For a better understanding of the invention, reference may be made to the accompanying drawings, in which

Fig. 1 is a view in side elevation of a thermometer, the stem of which has been provided with an enlargement of plug form by the practice of the new method;

Fig. 2 is a view in side elevation of a portion of the stem of the thermometer and illustrates the first step in the practice of the method;

Figs. 3 and 4 are longitudinal sectional views through the stem of the thermometer and illustrate subsequent successive steps in the method;

Fig. 5 is a longitudinal sectional view through the stem of the thermometer on which an enlargement has been formed by the method;

Fig. 6 is a longitudinal sectional view through the stem of the thermometer showing the enlargement in its final form;

Fig. 7 is a view similar to Fig. 3 but showing a step in a modified form of the method; and

Fig. 8 is a longitudinal sectional view of the final form of the thermometer stem and enlargement made by the method involving the operation of Fig. 7.

The thermometer shown in Fig. 1 has the usual glass stem 10 terminating at one end in a bulb 11 and formed with a capillary tube 12 leading from the bulb to the other end of the stem. Between its ends, and preferably nearer the bulb end, the stem is formed with an enlargement 13, which has an external ground surface of tapering diameter, so that the enlargement can be seated in a corresponding ground tapered socket to make a tight sealed joint.

In the production of the thermometer shown in Fig. 1 by the method of the invention, the stem 40 is first heated over narrow circumferential areas 14, 15 spaced apart a distance corresponding to the length of the enlargement to be made. The areas are heated separately by a flame and, when the glass in an area is softened, the ends of the stem are forced toward one another to cause the softened glass to bulge outwardly. Small similar circumferential collars 14a, 15a are thus formed and, since the external diameter of the collars is not substantially greater than that of the stem, 50 the collars can be readily made without distortion of the passage 12.

When the collars have been completed, a length of straight glass tubing 16 of uniform diameter and wall thickness and sufficiently long 55 to span the distance between the collars is slipped

over the stem and collars. The tubing preferably has an internal diameter not substantially greater than the external diameter of the collars and the wall thickness of the tubing is such as to provide the necessary amount of glass to make the enlargement. When the tubing has been placed in position, a flame, indicated at 17, is applied to the tubing outside one collar, for example, the collar 14a, and, as the tubing is heated, the stem and tubing are rotated and the glass of the tubing softens and seals to the outer surface of the collar at its plane of greatest diameter. A hose 18 is then telescoped over the stem and the end of the tubing 16 remote from collar 14a. The hose is connected to a vacuum pump and, with the pump operating, the flame is applied to the outer surface of the tubing adjacent collar 14a and the tubing is progressively heated toward collar 15a. As the tubing softens, it is collapsed against the surface of the stem by the vacuum and adheres to the stem, until finally the tubing is attached to the outer surface of the stem between the planes of greatest diameter of the collars.

The hose 18 is then disconnected from the end of the tubing and the free ends of the tubing beyond their planes of connection to the outer surfaces of the collars can be readily broken off and removed. Any sharp edges along the lines of fracture may be smoothed by means of the flame. The length of tubing that has thus been attached to the outside of the stem is substantially of the shape of the enlargement 19. Thereafter, the enlargement is finished by grinding its outer surface 20 to the desired final tapering diameter and, preferably, the surface 21 connecting the large end of the ground surface with the outer surface of the stem is given a light finishing grind.

In the modified form of the method illustrated in Figs. 7 and 8, the stem of the thermometer is heated as before at spaced points to form collars 22, 23, and collar 23, which is to lie at the large end of the enlargement, is of somewhat greater size than collar 22. After formation of the collars, a length of glass tubing 24 of a slightly greater length than the distance between the collars is slipped over the stem of the thermometer. The inner diameter of the tubing is not substantially greater than the outer diameter of collar 22 and the end 24a of the tubing is, accordingly, flared in a preliminary operation, so that it will telescope over collar 23. After the tubing is in place, the flared end is heated until it softens and seals to the outer surface of collar 23, after which the interior of the tubing is evacuated and heated to cause the tubing to collapse and adhere to the surface of the stem of the thermometer between the planes of greatest diameter of the collars. When the tubing has thus been attached to the stem, the free end of the tubing beyond collar 22 is broken off and the stem is thus formed with an enlargement, which can be ground to the final tapered form shown at 25. The ground surface lies approximately tangent to the surface of the large collar 23 and, as the surface 26 of the collar is smooth, it does not require any finish grinding.

With the method described, the stem of the article is subjected to only minor distortion to form the spaced collars at opposite ends of the enlargement and, in the case of a thermometer, the collars can be readily formed without distortion of the capillary tube. The use of the length of tubing makes the provision of the necessary body of glass to form the plug enlargement on

the article a simple operation and, by the new method, thermometers and other articles with an integral ground plug enlargement can be made rapidly and at low cost by relatively unskilled workers.

I claim:

1. In a method of forming a glass article with an enlargement receivable in a ground socket to make a tight joint, the steps of heating the article over narrow circumferential areas to soften it and forcing its ends together to form circumferential collars at spaced points, telescoping a length of glass tubing over the article, the tubing extending from one collar to the other, heating the tubing to soften it, and, while the tubing is being heated, evacuating its interior to cause it to be drawn inwardly to adhere to the article.

2. In a method of forming a glass article with an enlargement receivable in a ground socket to make a tight joint, the steps of heating the article over narrow circumferential areas to soften it and forcing its ends together to form circumferential collars at spaced points, telescoping over the article and collars a length of glass tubing extending from one collar to the other, heating the tubing adjacent one collar to cause the tubing to adhere to the collar entirely around the latter, evacuating the interior of the tubing between the collars, and heating the tubing progressively from the collar, to which the tubing is connected, to the other collar to soften the tubing, until the vacuum within the tubing draws it into contact with the article.

3. In a method of forming a glass article with an enlargement receivable in a ground socket to make a tight joint, the steps of heating the article over narrow circumferential areas to soften it and forcing its ends together to form circumferential collars at spaced points, telescoping a length of glass tubing over the article to enclose the collars and the portion of the article between them, heating the tubing at one collar until the tubing softens and becomes sealed to the surface of the collar, connecting the end of the tubing adjacent the second collar to a source of vacuum, progressively heating the tubing from the first collar to the second, until the tubing collapses against the surface of the article and adheres thereto, and breaking off free portions of the tubing beyond the collars.

4. In a method of forming a glass article with an enlargement receivable in a ground socket to make a tight joint, the steps of heating the article over narrow circumferential areas to soften it and forcing its ends together to form collars of approximately the same external diameter at spaced points, telescoping a length of glass tubing of substantially uniform internal diameter and wall thickness over the article and collars, heating the tubing adjacent one collar to cause the tubing to adhere to the article entirely around the latter, evacuating the interior of the tubing from its connection to the collar through the opposite end of the tubing, and, while the evacuation is continuing progressively heating the tubing from its connection to said collar to the other collar, until the tubing collapses and adheres to the article at and between the collars.

5. In a method of forming a glass article with an enlargement receivable in a ground socket to make a tight joint, the steps of heating the article over narrow circumferential areas to soften it and forcing its ends together to form circumferential collars at spaced points, one of the collars being of larger external diameter than the

other, telescoping a piece of glass tubing with a flared end over the article, the flared end overlying the large collar and the tubing extending past the small collar, heating the tubing at the flared end until the tubing adheres to the outer surface of the large collar, evacuating the tubing through the opposite end, and, while the evacuation is continuing, progressively heating the tubing from the large collar toward the small collar, until the tubing collapses against the other surface of the article and adheres thereto between and at the collars.

6. A method of forming a glass article with an enlargement receivable in a ground tapered socket to make a tight joint, which comprises heating the article to soften it over narrow circumferential areas and forcing its ends together to form circumferential collars at spaced points, telescoping a length of glass tubing over the article, the tubing extending from one collar to the other, evacuating the interior of the tubing, heating the tubing, while the evacuation is continuing, to cause the tubing to collapse and adhere to the article between and at the collars, and grinding the outer surface of the tubing to a tapering diameter.

7. A method of forming a glass article with an enlargement receivable in a ground tapered socket to make a tight joint, which comprises heating the article to soften it over narrow circumferential areas and forcing its ends together to form circumferential collars at spaced points, telescoping a length of glass tubing over the article, the tubing extending from one collar to the other, evacuating the interior of the tubing, heating the tubing, while the evacuation is continuing, to cause the tubing to collapse and adhere to the article between and at the collars, cutting off the tubing at the collars, and grinding the outer surface of the tubing to a tapering diameter.

8. A method of forming a glass article with an enlargement receivable in a ground tapered socket to make a tight joint, which comprises heating the article to soften it over narrow circumferential areas and forcing its ends together to form circumferential collars at spaced points, telescoping a length of glass tubing over the article, the tubing extending from one collar to the other, evacuating the interior of the tubing, heating the tubing, while the evacuation is continuing, to cause the tubing to collapse and adhere to the article between and at the collars, cutting off the tubing at the collars, grinding the outer surface of the tubing to a tapering diameter, and grinding the surface connecting the surface of the article with the large end of the tapered surface.

9. A method of forming a glass article with an enlargement receivable in a ground tapered socket to make a tight joint, which comprises heating the article over narrow circumferential areas to soften it and forcing its ends together to form circumferential collars at spaced points,

one collar being larger than the other, flaring one end of a straight piece of glass tubing having an internal diameter not substantially greater than the external diameter of the small collar, so that the flared end will receive the large collar, telescoping the piece of tubing over the article with the flared end receiving the large collar and the small collar lying within the portion of the tubing of uniform diameter, sealing the flared end of the tube to the surface of the large collar, evacuating the interior of the tubing, progressively heating the tubing from the seal at the large collar toward the small collar, while the evacuation continues, to cause the tubing to collapse and adhere to the surface of the article and the small collar, and grinding the outer surface of the tubing to a diameter tapering toward the small collar.

10. A method of forming a glass article with an enlargement receivable in a ground tapered socket to make a tight joint, which comprises heating the article over narrow circumferential areas to soften it and forcing its ends together to form circumferential collars at spaced points, one collar being larger than the other, flaring one end of a straight piece of glass tubing having an internal diameter not substantially greater than the external diameter of the small collar, so that the flared end will receive the large collar, telescoping the piece of tubing over the article with the flared end receiving the large collar and the small collar lying within the portion of the tubing of uniform diameter, sealing the flared end of the tube to the surface of the large collar, evacuating the interior of the tubing, progressively heating the tubing from the seal at the large collar toward the small collar, while the evacuation continues, to cause the tubing to collapse and adhere to the surface of the article and the small collar, cutting off the free end of the tubing beyond the small collar, and grinding the outer surface of the tubing to a diameter tapering toward the small collar.

11. In a method of forming a glass-stemmed thermometer with an enlargement of plug form receivable in a ground socket to make a tight joint, the steps of heating the stem of the thermometer over narrow circumferential areas to soften it and slowly forcing the ends of the stem together to form circumferential collars at spaced points without substantial distortion of the capillary tube through the stem, telescoping a length of glass tubing over the stem, the tubing extending from one collar to the other, heating the tubing to soften it, while evacuating the interior of the tubing to cause it to collapse and adhere to the surface of the stem, cutting off the tubing at the collars, and grinding the external surface of the tubing to a diameter tapering toward the bulb end of the thermometer.
